UNITED STATES PATENT OFFICE.

FRED KESTLER, OF BIRMINGHAM, ALABAMA.

DROP-DOOR CONSTRUCTION.

1,284,111.

Specification of Letters Patent.

Patented Nov. 5, 1918.

Application filed March 26, 1917. Serial No. 157,416.

To all whom it may concern:

Be it known that I, FRED KESTLER, a citizen of the United States, residing at Birmingham, in the county of Jefferson, State 5 of Alabama, have invented certain new and useful Improvements in Drop-Door Constructions, of which the following is a specification.

The present invention has reference to 10 certain improvements in drop door mechanism for freight cars generally, and particularly for freight cars of large capacity and has reference to the arrangement of the mechanism and its combination with the drop doors with which it is intended to operate. My invention provides a means for operating the mechanism manually or pneumatically.

It is one of the objects of my invention 20 to simplify and strengthen all component parts of said door mechanism, thereby avoiding the necessity of holding the doors closed by means of chains, worm wheels, tumbling shafts and other parts such as 25 exist in the present day door construction and mechanism.

By my invention it is sought to eliminate 30 the strain on the door chains and gear wheels, thus overcoming the loss of lading on account of broken chains and preventing the lading from falling while the train is in motion. The particular design of the car and slope sheets permits the lading to be unloaded between the rails, thereby 35 avoiding the usual damage to the girders of the bins, particularly when a large amount of heavy lading is constantly falling against the girders.

My invention permits the door, floor and 40 slope sheets to be installed on an angle of 45 degrees, which renders the car self cleaning and thus avoids the necessity of labor in unloading. By my invention the doors may be opened and closed in a short space 45 of time which permits rapidity in unloading the cars.

My invention provides a locking device 50 which is housed in a specially formed casting, held in position by any suitable means and situated between the sills of the car, thereby strengthening the sills by tying them together. The locking device is so constructed that the static strain and pressure on the doors is transferred to the pivot 55 blocks and the transmission arms counter-balancing the weights on each door.

My invention provides various other features of improvement hereinafter referred to.

The accompanying drawings illustrate one 60 embodiment of the invention.

Figures 1 and 2 are cross-sections with the doors closed and open respectively;

Fig. 3 is a plan of the pivot blocks and 65 related parts when the doors are closed;

Fig. 4 is a plan of the same parts when the doors are open;

Figs. 5 and 5^a are longitudinal and cross-sections of a detail provided for supporting 70 the pivot bars;

Figs. 6 and 6^a are detail views illustrating 75 the construction of the pivot blocks;

Fig. 7 is a broken plan of the winding worm and related parts;

Fig. 8 is a longitudinal view (partly in 75 section and partly in elevation) of the connections on the ends of the pivot bars;

Fig. 9 is a cross-section on the line 9—9 80 on Fig. 7;

Fig. 10 is a cross-section on the line 10— 80 10 on Fig. 9;

Fig. 11 is an end elevation.

The doors 1 are connected to the door castings 2 by bolts and rivets 3. The castings are made in two parts and are provided with 85 sockets 4 into which fit the arms 5 forming a ball and socket joint. The arms are connected at their opposite ends to the pivot blocks 6 by the pins 7. Each pivot block has two jaws 8 connected together at the 90 top by a web 9, the recess thus formed between the jaws and under the web having a curved inside wall against which the curved end of the arm 5 bears when the car doors 1 are being closed or held closed, thus 95 reducing the strain on the pins 7 when the doors are in said position.

The pivot blocks 6 are joined by and rotatable around a pin 10 forming a hinge joint. Each pivot block has a wing 11 100 which comes in contact with the wing of the opposite pivot block when the joint is fully open, the doors 1 then being closed. These wings 11 are each notched or cut away at 11^a on the portion of their lower face which is 105 directly over the pivot bar 13 when the joint is open for the purpose of preventing collection of waste material on the top of the pivot bars and between the wings 11 which would obstruct a full opening of the joint. 110 The pivot bars 12 and 13 are joined by the pin 10 to the pivot blocks,

A door stop 14, being a curved flat spring, is attached to the outside of the web of the center sills 15 by the rivets or bolts 16 for the purpose of preventing the doors 1 from 5 swinging beyond a vertical position.

The pivot bars 12 and 13 located between and below the center sills 15 are connected with each pair of pivot blocks 6 and extend from a cylinder 16 located near one end of 10 the car, to the lock 17 at the other end of the car. The pivot bars are fastened together at their ends by means of blocks 18 and 19 which are of sufficient thickness to hold the bars at their proper distances apart 15 and which are connected to the pivot bars by bolts 20, thus causing them to act as one bar.

The said pivot bars 12 and 13 are held in position by several supports 21 which are 20 locked adjacent to each pair of pivot blocks and attached to the center sills 15. The chain 22 is secured at one end with the worm gear 23 around which it is wound by means of a wrench on the end of the shaft 24 which 25 forms a part of the manually operatable mechanism and said chain 22 is fastened at its opposite end to the flange 25 which is a part of block 19.

The chain 26 is also connected to the 30 worm gear 23 and at its opposite end to the pivot bar 12 by means of the strap 27.

A pivot bar support is provided which comprises a frame 21 with flanges 28 on each side which are connected to center sills 15 35 by bolts and has two hanging guides 29 connected together at the bottom for the purpose of strengthening them. These guides support the bearing spool 30 by means of the pin 31 which passes through the two guides 40 and the spool so that the pivot bars may move horizontally with the length of the car. The pivot bar 12 is supported on the top of said spool.

A locking device is provided for holding 45 the doors closed, 32 being a housing containing the vertical slide 33 and the gear wheel 34 on the shaft 35, which extends through the side of the car. This housing has two top flanges 36, which rest on the center sills 50 15 and are fastened thereto by rivets 37; the two vertical ribs 38 supporting the shaft 35 on which is the gear wheel 34. The said gear wheel operates on the geared slide 33, thus causing said slide to be moved down- 55 ward to form a stop for the pivot bars 12 and 13 thereby holding the doors closed, or moved upward to clear said pivot bars, thereby allowing the doors to be opened. The studs 39 on each side of the slide pre- 60 vent said slide from dropping or being lowered out of place.

On the end of the shaft 35, which extends outside of the car is a hand wheel 40, for turning said shaft, thereby raising or lowering the slide 33. On the shaft 35, there

is a disk 41 with reversible notches, and a pawl 42 for holding the shaft as turned in either direction. The said pawl is fastened by a bolt 42a.

The cylinder 16 is supported between the 70 center sills 15 by means of a hanger 43 by bolts 44 and the piston of said cylinder is connected to the pivot bar 12 by a strap 45, for the purpose of opening and closing the doors pneumatically. Said piston is controlled by a suitable four way valve operated with a lever 46 which lever is provided with a lock 47.

The doors are closed manually by means of the mechanism comprising its shaft 24 on 80 which is located the worm gear 23 on one end and the gear wheel 48 on the other end. This gear wheel 48 engages a smaller gear wheel 49 on the shaft 50 which extends to the outside of the car. The said gear wheels 85 48 and 49 are contained in a housing 51 which is riveted or bolted to the side of the car and on the inside thereof. The shaft 50 is provided with a ratchet wheel 52 and a pawl 53 attached to the outside of the car 90 for the purpose of holding the doors from open to closed when they are being operated manually.

What I claim is:

1. In a drop door operating mechanism, 95 the combination of a pair of doors located opposite each other, a longitudinally movable toggle operating rod located between the two doors, pivot blocks forming a hinge joint, a pin for holding the same together, 100 each of said pivot blocks comprising a wing adapted to press against the wing of the other when the doors are closed, and arms connecting said pivot blocks to said doors, the strain on one door being transmitted 105 directly to the other through said wings when the doors are closed, without substantial strain on the operating rod.

2. In a drop door operating mechanism, 110 the combination of a pair of doors located opposite each other, a longitudinally movable toggle operating rod located between the two doors, pivot blocks forming a hinge joint, a pin for holding the same together, 115 each of said pivot blocks comprising a wing cut away on the lower face thereof so as to pass over obstructions accumulated on the operating rod, said wings adapted to press against each other when the doors are closed, and arms connecting said pivot blocks 120 to said doors, the strain on one door being transmitted directly to the other through said wings when the doors are closed, without substantial strain on the operating rod.

3. In a drop door operating mechanism, 125 the combination of a pair of doors located opposite each other, a longitudinally movable toggle operating rod located between the two doors, pivot blocks forming a hinge joint, a pin for holding the same together, 130

- each of said pivot blocks comprising a wing adapted to press against the wing of the other when the doors are closed, jaws at the outside end of each pivot block, a web connecting the jaws together, a recess formed between the jaws and under the web having a curved inside wall, an arm fitting in said recess, a pin for holding the same, said arm connecting one of the pivot blocks with one of the doors, the strain on one door being transmitted directly to the other through said wings when the doors are closed, without substantial strain on the operating rod.
4. In a drop door operating mechanism, the combination of a pair of doors 1 located opposite each other, longitudinally movable toggle operating rods 12 and 13 located between the two doors, pivot blocks 6 forming a hinge joint attached to said toggle operating rods by a pin 10, said pivot blocks comprising wings 11 adapted to press against each other when the doors are closed and cut away on their lower faces 11^a to pass over foreign matter on the operating rod 13 thereby permitting freedom of operation of said wings, each pivot block comprising jaws
- 8 and a web 9 on the outside end thereof, arms 5 fitting in the recess formed by said jaws and web, said arms being connected to said pivot blocks by pins 7 whereby the strain on one door is transmitted directly to the other through said wings when the doors are closed, without substantial strain on the operating rod.
5. In a drop door operating mechanism, the combination of doors and pivot blocks and arms for connecting the same, operating rods and means for longitudinally moving the same whereby said doors are opened and closed, and a locking device for holding said doors closed comprising a housing, a vertical slide contained therein, a gear wheel, a shaft on which the same is mounted, means for rotating said shaft whereby the vertical slide is raised or lowered into the locking position preventing the operating rods from moving longitudinally, and studs on each side of the vertical slide to prevent the same from dropping or being lowered out of place.

In witness whereof, I have hereunto signed my name.

FRED KESTLER.
